GRIP FOR CABLE RAILWAYS.

No. 353,713.

Patented Dec. 7, 1886.

Inv. Charles Scholz
By Wm. H. Potts
N.Y.C.

UNITED STATES PATENT OFFICE.

CHARLES SCHOLZ, OF CHICAGO, ILLINOIS.

GRIP FOR CABLE RAILWAYS.

SPECIFICATION forming part of Letters Patent No. 353,713, dated December 7, 1886.

Application filed April 13, 1886. Serial No. 198,759. (No model.)

To all whom it may concern:

Be it known that I, CHARLES SCHOLZ, a subject of the Emperor of Germany, residing at Chicago, in the county of Cook and State of Illinois, have invented certain new and useful Improvements in Grips for Cable Railways, of which the following is a specification, reference being had therein to the accompanying drawings.

The nature of my invention relates to certain improvements in grips for cable railways, described in Letters Patent of the United States No. 325,633, issued to me on September 1, 1885 and also in application for Letters Patent, Serial No. 183,062, filed by me on November 17, 1885; and it consists of the novel devices and combinations of devices hereinafter described and specifically claimed.

In the accompanying drawings, Figure 1 represents a side elevation of the grip as tightened upon the cable; and Fig. 2, a similar view of the same opened wide enough to disengage and throw off the cable. Fig. 3 is a similar view again, with the cable engaged and showing by dotted lines the position of parts for automatically disengaging the cable. Fig. 4 is an edge view, Fig. 5 a vertical section of the grip, and Fig. 6 an enlarged sectional view of parts thereof; Fig. 7, an elevation of the movable jaw-frame detached, and showing the journal-box in dotted lines; and Fig. 8, a longitudinal vertical section of the upper jaw.

Corresponding letters in the several figures of the drawings designate like parts.

A denotes the beam that is rigidly suspended and secured under the floor of the car, and to which all the parts composing the cable-grip are connected. To the top of this beam A is rigidly secured an arch-plate, B, having a series of ratchet-teeth, *a*, to one end, and two such ratchet-teeth, *a'*, to its opposite end, and to beam A is also rigidly connected the pendent plate C, that to its lower end has the upper jaw, D, of the cable-grip. The lower jaw, E, is secured to a frame, F, the parallel side bars of which embrace the plate C and pass through slotted openings in beam A, and in upper grip-jaw, D, to be vertically guided therein. The upper curved connecting-bar of this frame F is vertically slotted for the two guide-arms, *b*,

of a journal-box, G, that is vertically adjustable thereon by a set-screw, *c*, tapped through such connecting-bar, and, with its point, is pivotally secured into a socket of box G. The 55 trunnion of a lever, H, is journaled in box G, and its protruding end has secured to it a crank, I, which crank stands in line with the tail end of lever H, both being pivotally connected with beam A by links J, that, together with such lever end and with such crank I, form toggle-joints, by which the lower jaw is lifted for clamping the cable with great force. These cranks, as will be noticed, are placed on a sufficient angle relative to lever H to require about the full sweep of such lever in one direction for moving the cranks to a straight line with the links J. The cranks being rigidly connected with lever H, while the links are pivoted at both ends, the height of frame 70 F and lower jaw, E, will be changed with every movement of the lever H from right to left, or reversely. This change is due to the relative position of the links with respect to the cranks I and lever H.

As shown in Figs. 1 and 2, the toggles, which are formed by cranks I and links J, are differently disposed. In Fig. 1 the cranks and links are about perpendicular, the lever H is thrown well toward the right, and the jaw E 80 is clamped up tight against the cable; while, as shown in Fig. 2, the position of the toggles is changed, so that their points of connection to lever H and bar A are nearer to each other, and the jaw E is dropped out of engagement 85 with the cable, and lever H is thrown well to the left.

It is not necessary to throw the lever H any farther toward the right than is shown in Fig. 1; but it will be understood that the relative 90 positions or angles of the different members composing the toggle may be varied at will, so that the throw of the lever H can be varied as desired to effect the engagement and disengagement of the cable.

To lever H is pivotally connected a pawl, *d*, engaging with the ratchet teeth *a* or *a'*, the tail end of which pawl, by a rod, *e*, is coupled with the tail end of an auxiliary handle, *f*, pivotally connected with the handle portion of the lever H in such a manner that by contracting 100 the two handles the pawl *d* is lifted out of en-

gagement with the ratchet, and by releasing the handles *f* the pawl *d* is pushed into engagement with such ratchet-teeth by a spring, *h*.

5 An arch-shaped bar, *K*, is pivotally secured with its center to the center of arch-bar *B* by a bolt, *i*, in a manner to be vibratable thereon, and the pawl *d* is sufficiently wide to extend transversely over the edge of bar *K* 10 in a manner that a vibration of such bar *K* will lift the pawl *d* out of contact with the ratchet-teeth *a* of bar *B*, when the lever *H*, by the action of a spring, *j*, and by the tension of the cable, will be shifted to swing to the opposite side for the pawl *d* to engage with one 15 of the ratchet-teeth, *a'*, thereby dropping the lower jaw to be wide open.

A supplementary frame, *L*, consisting of two vertical bars exterior of frame *F*, also 20 movably guided in the slotted openings of beam *A* and conected on top by a longitudinal bar shaped like the top bar of frame *F*, and connected near their bottom ends by two bars, *k*, one against each side thereof.

25 To the center of each bar *k* is pivotally secured a roller, *m*, and to one end of the upper bar of frame *L* is fixed a cam-extension, *n*, engaging with the rounded end of bar *K*. A cam-plate, *l*, secured against the crank part of 30 lever *H*, will support frame *L* to follow the vertical movements of frame *F* when raised and lowered by lever *H*, and by still swinging the lever farther after the grip has been opened. This cam *l* will lift frame *L* for throwing off 35 the cable by the action of rollers *O*, as will be hereinafter explained, and is shown in Fig. 2.

In places where the grip has to release one cable to cross another, or for other reason, the 40 cable might be torn if the driver should forget to open the grip in proper time, or without some safety attachment that will release and throw off the cable from the grip automatically, and for this latter purpose I secure 45 within the cable-tunnel in proper position wedges *M*, that, with the car moving by them, their pointed ends will engage under rollers *m*, and then with passing over the incline of such wedges the frame *L* will be lifted, when 50 the cam-extension *n* will press under the end of arch-bar *K*, and will swing such arch-bar to lift the pawl *d*, thereby releasing lever *H*, that will swing to its opposite position and will drop the lower jaw of the grip, and after 55 passing the wedges *M* the frame *L* will drop again by its own gravity to find its support on cam-plate *l*.

The base-plate of the lower jaw, *E*, is extended beyond the concaved jaw-plates proper, and 60 to both ends it has pivoted sheaves or rollers *N*, on which the cable rides while the car is slackened or stopped, which rollers may be made vertically adjustable, and upon this base-plate are also secured vertical studs *p*, 65 forming the pivots for rollers *O*, which rollers at their bottom ends are provided with conical flanges. These rollers *O* have each turned a

journal in their upper ends, that is held in a guide-loop, *o*, secured to the lower extremities of the side bars of frame *L* with a collar or 70 head to the top end of each roller, that prevents its disengagement from such guide-loop, and causes such rollers to follow the upward movement of frame *L* when lifted by its roller *m*, riding over wedge *M*, or when lifted by lever *H*, whereby the conical flanges of such rollers will shift the cable sidewise off the rollers *N* and off the lower jaw of the grip. Sufficient free vertical play is provided for the 75 journals of rollers *O* in their loops *o*, that the simple releasing of the cable for stopping or slackening the car will allow the rollers *O* to follow the motion of the lower jaw.

While the lower jaw, *E*, is rigid with its frame, the upper jaw, *D*, has a shoe, *R*, connected therewith by a series of pivotal links, *v*, that with moving the shoe *R* in the pulling direction of the cable will come to a vertical or nearly vertical position, but with a pull in the opposite direction will release the 90 cable, for the purpose that with a sudden slackening of the speed of the cable or with an irregular motion thereof the car is independent of the movement of the cable when it runs faster, but will be coupled again the 95 moment its speed becomes less than the cable. A spring, *w*, to each link *v* will assist in the ready releasing of the cable by shoe *R*.

It frequently happens with cable railways that when a horse crosses the track one of the 100 carks of its shoes wedges into the cable-grip slit, whereby such shoe will come off the horse's hoof and will remain an obstruction to the cable-grip, and is apt to break it or the cable, and therefore as a safeguard I put extensions 105 *r* and *s* to the pivotal arch-bar *K*, each such extension reaching into the track-slit, so that no matter in what direction the car moves one of the extensions that is forward will have to meet the obstruction in advance of the grip-pendant, the object being to produce a forcible vibration of arch-bar *K*, that will disengage pawl *d* of lever *H* from the ratchet-teeth of arch-piece *B* in the same manner as with the lifting of frame *L* by wedge *M*, thereby releasing the cable without, however, throwing it off the lower jaw of the grip. For this purpose one of the extensions, *r*, is made solid with arch-bar *K*, while for producing the required movement of such arch-bar from the opposite 110 direction the extension-bar *s* is a separate piece pivotedly secured to beam *A* at *t* and coupled with the arch-bar *K* by a bolt, *u*, passed through the slotted ends of both.

As will be readily seen, with the above-described safety devices accidents that would cause the breaking of the cable are entirely obviated.

Instead of arch-bar *K* and frame *L* with roller *m*, other suitable devices may be applied 130 for lifting pawl *d*; nor is it essential that piece *M* should be wedge-shaped or an incline, since a bell-crank connected with its horizontal arm to pawl *d* by a rod and with its pendent arm

striking against any projecting fixed piece in the cable-tunnel would accomplish the same object, and therefore I do not wish to be restricted to the particular construction herein shown and described.

5 What I claim is—

1. The combination, with the toothed bar B, lever H, and pawl d, of the supplemental bar K, pivoted to bar B and capable of covering its 10 entire line of ratchets a, and connections, substantially as described, to the lower portion of the grip to be acted upon by a projection in the tunnel, as and for the purpose set forth.

2. In a cable-grip, the combination, with 15 toothed arch-bar B and with lever H, having pawl d, of pivotal bar K and frame L, with roller m, to engage with a stationary incline, all substantially as described, to operate as specified.

20 3. The combination, with stationary inclines arranged within the cable-tunnel, of a cable-grip having toothed arch-bar B and operating-lever H, with pawl d, and being provided with pivotal bar K, and frame L, with rollers m and 25 cam n, and connecting mechanism, substantially as described, between frame L and lever K, all constructed and arranged, substantially as set forth, to operate as specified.

4. The combination, with stationary inclines arranged within the cable-tunnel, of a cable-grip having toothed arch-bar B and operating-lever H, with pawl d, and being provided with pivotal bar K, and frame L, having roller m, cam n, and rollers O, all constructed and 30 arranged substantially as and for the purpose set forth, to operate as specified.

5. In a cable-grip, the combination of the movable lower jaw, E, the vertically-sliding frame F, to which said jaw is attached, the lever H, links J, and cranks I, with beam A and 40 bar B, substantially as set forth.

6. In a cable-grip, in combination with toothed arch-bar B and with operating-lever H, having pawl d, the pivotal bar K, having extensions r and s, that reach into the cable-grip 45 slit, substantially as and for the purpose set forth.

In testimony whereof I affix my signature in presence of two witnesses.

CHARLES SCHOLZ.
